(57) CLAIM

The ornamental design for a combined hair dye container and dispenser, as shown and described.

DESCRIPTION

FIG. 1 is a front view showing a combined hair dye container and dispenser according to the present invention, the rear view being a mirror image thereof;

FIG. 2 is a plan view showing the combined hair dye container and dispenser of FIG. 1;

FIG. 3 is a left view showing the combined hair dye container and dispenser of FIG. 1;

FIG. 4 is a right view showing the combined hair dye container and dispenser of FIG. 1; and,

FIG. 5 is a perspective view showing the combined hair dye container and dispenser of FIG. 1.

The surface or portion of the article not shown in the drawing or described in the specification forms no part of the claimed design.
